UNITED STATES PATENT OFFICE.

CLARENCE SAMUEL MARDEN, OF ALBANY, NEW YORK.

TOY.

Application filed November 7, 1927. Serial No. 231,426.

This invention relates to toys and has for its object the provision of a set of toy houses adapted primarily for out of door play, as on the beach or sand pile, and of a character such as to be virtually indestructible by either rough handling or the action of the elements.

A further object of the invention is the provision of a toy house or set of houses made of solid wood but which nevertheless present a pleasing attractive appearance closely simulating the appearance of actual houses.

A further object of the invention is to provide a set of houses arranged in a block, the individual houses being of different design and appearance whereby with a different arrangement of the houses the appearance of the resulting block may be widely varied.

In the accompanying drawings I have illustrated a number of houses of different designs embodying my invention.

In said drawings

Fig. 1 represents a group of houses arranged in a row and detachably supported on a common base;

Fig. 2 is a transverse vertical section on line 2—2 of Fig. 1;

Fig. 3 is a perspective view of one of the houses shown in Fig. 1 but removed from the base;

Figs. 4 and 5 are perspective views showing houses of different design adapted for use with the base shown in Fig. 1; and

Figs. 6 and 7 are perspective views of houses of still further types designed for use as separate units.

Referring to the drawings, particularly Figs. 1, 2 and 3, 1 indicates a supporting board or base upon which the separate houses are to be assembled. The base consists of a substantial board and is preferably painted and varnished so as to be waterproof. The board is wider than the corresponding dimensions of the houses which are assembled thereon so as to provide a street or walk along the front of the houses, and if desired the edge of the board may be painted with paving stones or the like.

Each of the houses, of which five different types are shown in the drawing, consists, as shown in Fig. 3, of a solid block of wood 2 of rectangular cross section with the grain running vertically of the house so that the

side walls of the house may be dressed to a smooth surface for painting. For example, the houses may be cut from a dressed timber, preferably white pine or other light wood of standard dimensions, say 4" x 3". The bottom surface of the house is flat to fit on the baseboard or other support and the top of the house is preferably cut to simulate the lines of a roof, preferably an ordinary gable roof with a single ridge extending from end to end of the house, although other types of roofs may be provided, as shown, for example, in Figs. 1 and 7.

The faces of the block forming the roof are covered with real roofing, preferably of the so-called slate granule type consisting of a sheet of heavy asphaltic fabric or paper with the outer surface covered with a layer of crushed slate. The sheet roofing 3 is cut large enough to provide eaves, as shown at 4, both in the gable ends of the house as well as at the side edges. The roofing is preferably in one sheet and creased along the middle to bend over the ridge of the roof. The sheet of roofing may be fastened to the house in any desired manner, but as the toy is primarily intended for outdoor play it is preferably nailed in place with brass nails rather than attached with glue alone.

The side walls of the house have windows and doors painted thereon in colors contrasting with the color of the house itself, and after painting, but before the roof is applied, the houses are preferably sprayed with marine varnish to render them thoroughly waterproof to prevent warping or cracking of the wood.

To further add to the appearance of the houses they are provided with chimneys 5 or the like, which are preferably made also of solid wood and attached to the houses by nailing. The chimneys may be attached over the roofing as shown in Fig. 2, or may be nailed to the end or side faces of the house as shown in Fig. 7.

Each of the houses is designed for use with the base 1 and is provided with an undercut groove 9 in its bottom face extending parallel with the front of the house, and cooperating with a guide strip 10 attached to the board 1, the guide strip being preferably formed of brass or other non-corroding metal and of a shape to fit the groove in the manner shown in Figs. 1 and 2.

Buildings other than dwelling houses may

be simulated in an attractive manner without materially adding to the cost of the toy. In Fig. 4 there is shown, for example, a store building which, as shown, comprises in addition to the roof 3 and chimney 5, a triangular piece 12 nailed to the front wall to represent the awning extending over the show windows.

In Fig. 5 a church building is shown wherein the appearance of a church is secured by the provision of a steep roof and a tower or steeple 11 formed of a stick of solid wood and nailed to the end of the block. Similarly the fire house shown in Fig. 6 is formed with the addition of a single piece 13 representing the conventional hose tower which usually forms part of a village fire house. In a similar manner other types of buildings, such as school houses, railroad stations, etc., may be provided by means of a block or strip of appropriate shape nailed to the block which forms the house proper.

By the use of real roofing for the roof of the house the appearance of the house and its likeness to a real building is greatly enhanced, due largely to the fact that the projecting edges of the roofing provide eaves of about the right proportion to the size of the house as employed in actual houses. That is to say, the thickness of the sheet of roofing fabric bears about the same relation to the size of the house as the depth of the roof structure compares with the size of an ordinary frame dwelling. Furthermore, the roof material, like the solid blocks of painted wood from which the houses are formed is substantially unaffected by the weather, and the houses may be left out of doors indefi-

nitely without deterioration or disintegration, as is the usual fate of fabricated toys. 40

I claim:

1. As a new article of manufacture, a toy house consisting of a solid block of wood forming the body of the house and a sheet of commercial roofing attached thereto and forming the roof thereof, said roofing extending beyond the edges of the surface to which it is attached to simulate the eaves of the house. 45

2. As a new article of manufacture, a toy house consisting of a solid block of wood forming the body of the house and a sheet of commercial roofing attached thereto and forming the roof thereof, and blocks simulating chimneys nailed thereto. 50

3. In a set of toy houses the combination of a baseboard, a plurality of houses adapted to be supported thereon, and means for detachably connecting the houses to the baseboard, grooves in the bottoms of said houses, and a rib on said baseboard having a sliding fit in said groove. 55

4. As a new article of manufacture, a toy house consisting of a solid block of wood having one flat face forming the bottom surface of the house, the opposite side being shaped to simulate a gable roof, and a piece of commercial roofing bent over the ridge of the roof and attached to the faces thereof, the thickness of said roofing having the same relation to the size of the block that the depth of the entire roof structure bears to the size of a real dwelling house. 60 70

In testimony whereof I affix my signature.

CLARENCE SAMUEL MARDEN.
